UNITED STATES PATENT OFFICE

JAMES E. DILLON, OF MASONTOWN, PENNSYLVANIA

MINING MACHINE

Application filed October 12, 1928. Serial No. 312,132.

This invention relates to mining machines, and particularly to means whereby the cutter bar may be swung laterally toward or from the track center while the machine is being moved around curves or switches of short radius.

Machines of this character project beyond the front axle such a distance as to make the movement of the machine from place to place

impossible unless some of the unsupported length of the machine projecting beyond the front axle is capable of movement relative to the center of the roadway. The cutter bar of these machines is ordinarily about ten feet long and pivoted at the rear end, which permits the cutter bar to be swung laterally in one direction or the other toward the track center so that it will not strike an entry or pillar while the machine is being moved around curves. This movement for steering purposes must be relatively rapid. Heretofore this movement of the cutter bar for steering purposes has been accomplished by manual means, as for instance, by an operator pushing on the cutter bar to shift it.

The general purpose of the present invention is to provide an auxiliary motor mounted upon the mining machine in connection with the swinging cutter bar and so connected to the cutter bar as to cause its swinging movement in one direction or the other in order to steer the machine while the machine is moving without actuating the cutters of the cutter bar.

A further object is to so connect this auxiliary motor to the cutter bar swinging and knife operating mechanism, that the usual driving shaft, whereby the cutter bar is fed and the cutting chain operated, may be disengaged from the cutter bar and the cutting mechanism and the cutter bar swung by this auxiliary motor, the auxiliary motor being an electric motor and connected in any suitable electric circuit including a controller for the purpose of driving the auxiliary motor either in one direction or the other to thus swing the cutter bar in one direction or the other for the purpose of steering the machine.

A further object is to provide a mechanism of this character which will swing the cutter

bar independently of the movement of other parts of the machine to thereby facilitate the transportation of the machine and effect a saving in the time required to position the machine to cut coal. This saving of time secures an increase in the productive efficiency of the machine of approximately 25% and also considerably reduces the transportation hazard.

Other objects will appear more fully in the course of the following description.

My invention is illustrated in the accompanying drawings wherein—

Figure 1 is a top plan view of a mining machine having my improvement applied thereto;

Fig. 2 is a side elevation of the forward end of the machine showing my improvement;

Fig. 3 is a horizontal section on an enlarged scale showing the mechanism whereby the cutter bar is swung;

Fig. 4 is a detailed view of the clutch whereby the supporting bracket for the cutter bar is engaged with the worm wheel;

Fig. 5 is a diagram showing the motor and the reversing switch; and

Fig. 6 is a fragmentary section on the line 6—6 of Fig. 3.

In the drawings I have illustrated the common and well known type of mining machine which includes the body 10 mounted upon wheeled truck 11, the body being provided with a cab 12 at the rear end, and the motor 13 with the usual controls. Mounted upon the forward end of the body is the neck 14 which is the term by which this part is known in the trade, and carried upon this neck is the link 15 and the sublink 16. All these parts are common and well known and require no particular description. Mounted upon the forward end of the link 15 is the head 17 within which is disposed a shaft 18 upon which is mounted the sprocket wheel 19. The cutter bar designated 20 is of the usual form adapted to provide a channel for an endless chain 21 carrying cutters 22. The means whereby the shaft 18 is rotated and the endless chain of cutters operated forms no part of the present invention and

may be of any usual or suitable character. The cutter bar is supported by means of a forked supporting bracket 23 which extends above and below the head 17 and is rotatable around an axis coincident with the axis of the shaft 18. Mounted above the upper branch 24 of the fork is a worm wheel 25 and associated with the bracket 23 is means designated generally 26 whereby the bracket 10 may be clutched directly to the worm wheel 25 or unclutched therefrom so as to leave the bracket free to be shifted or swung laterally independently of the wheel 25.

The clutch 26 is a half worm, the blank 15 side of which is turned to the worm wheel 25, when the clutch is disengaged. The threaded side engages the worm wheel 25 when the clutch is engaged.

The worm wheel 25 is ordinarily swung laterally for feeding movement by the following mechanism: Disposed within the sub-link 16 and mounted in suitable bearings therein is a traverse shaft 27 which carries upon it at one end the bevel gear wheel 28 25 in turn meshing with a pinion 29 on a shaft 30 which carries upon it the worm 31. This worm engages a worm wheel 32 mounted upon a worm shaft 33, this shaft being mounted in suitable bearings upon this sub-link. 30 The worm shaft 33 in turn engages the worm wheel 25. The shaft 27 is commonly driven by means of the two opposed bevel gear wheels 34 and 35 loosely mounted upon the shaft 27, as for instance upon sleeve 36 carried by this shaft. Disposed between these bevel gear wheels 34 and 35 is a driving pinion 37 mounted upon a driving shaft 38 having operative engagement with the shaft section 39 which in turn extends to or is operationally driven from the motor 13 or any other suitable motor. Mounted upon the shaft 27 is the sliding clutch 40 which is shiftable by means of the usual shipper lever 41 into engagement with one or the other of the gear wheels 34 or 35. By these means the shaft 27 may be driven in opposite directions and thus the worm wheel 25 shifted in one direction or the other to thus shift the cutter bar or swing it in one direction or the other. 50 So far I have described mechanism which is commonly found on mining machines of the type indicated. Commonly, however, the shaft 27 terminates at the dotted line α .

My invention contemplates the extension 55 of this shaft 27 transversely through the sub-link 16 at both ends and the mounting on the end of the shaft 27 opposite the gear wheel 28 of a bevel gear wheel 42. This is engaged by a bevel pinion 43 constituting the commutator shaft of the electric motor designated generally 44.

This electric motor is connected by suitable conductors to a source of current and to a reverse controller 46 whereby the current passing to the motor may be either cut off en-

tirely or reversed. When the current is cut off entirely and the shaft 39 is operating, then the cutter bar will be caused to swing by the usual and commonly found mechanism, well understood by those skilled in the art. If however, the clutch 40 be placed in its neutral position, then the cutter bar may be swung by means of the motor 44 acting through the train of mechanism which I have stated.

The cutter chain 21 is, of course, driven by mechanism disposed within the head 17 as is usual in mechanisms of this character and is not controlled or operated by the worm wheel 25 which worm wheel is merely for the purpose of shifting the cutter bar supporting mechanism. The neck 14 is mounted as usual for rotation around a longitudinal axis and this permits the cutter bar to be swung either vertically or horizontally at an angle, 75 between the vertical and horizontal, depending, of course, upon the position of the neck 14 relative to the body of the machine. This construction forms no part of my present invention but is present in mining machines of 80 this class.

The function of the cutter bar feed shaft 39 is to feed the cutter bar across the face when cutting coal. This movement of the cutter bar is of necessity very slow ranging, 85 from twenty-two inches per minute to twenty-four inches per minute and in this class of machines this feeding movement of the cutter bar can only be accomplished when the cutting mechanism is in operation and is, 90 much too slow to serve as a means for swinging the cutter bar while the machine is being moved about the mine.

If the cutter bar were swung at this slow rate while the machine was being transported, it would greatly retard the transportation of the machine and create a hazard by allowing the cutter and mechanism to operate while moving the machine. The rate of movement of the cutter bar desired when the machine is travelling and in order that the machine may be steered in a more or less circuitous course through entries or by pillars and while the machine is being moved around short curves should be approximately thirty-five feet per minute and my construction provides a power unit and control for the cutter bars of mining machines which is operable independently of the operation of other parts of the machine and which does away entirely with the necessity of disconnecting the cutter bar from its shaft and cutter driving mechanism and then manually shifting the cutter bar. While I have illustrated the particular arrangement of the 110 parts which have been found to be very effective, I do not wish to be limited thereto as the mechanism might be modified in many ways to embody the same principle of operation without departing from the spirit of 115

120 125 130

the invention as defined in the appended claims.

What I claim is—

1. In a mining machine of the character described, a cutter bar mounted for swinging movement, means for swinging, the cutter bar including a worm wheel and worm, means for driving the cutter bar including a transverse shaft having a driving connection to the worm, opposed bevel gear wheels loosely mounted upon the shaft, an intermediate power driven bevel gear engaging both of the first named bevel gear wheels, a clutch for operatively connecting the shaft to either one of the first named gear wheels or disconnecting the shaft from either of the bevel gear wheels, a bevel gear wheel mounted upon said shaft for rotation therewith, an electric motor having its armature shaft operatively engaged with the last named bevel gear wheel, and a reversing controller for said motor whereby the cutter bar may be shifted either by the main power operated shaft or by said motor.
2. In a mining machine of the character described, a body, a neck, a link mounted upon the neck for movement in a vertical plane, a sub-link operatively mounted upon the neck and above the link for movement with the link in a vertical plane, a head pivotally engaged with the link and sub-link to maintain a horizontal position in all positions of the link and sub-link, a cutter bar rotatably supported upon the head for swinging movement, means for rotating the cutter bar including a worm wheel adapted to be operatively engaged therewith, a worm shaft engaged by the worm wheel, a worm wheel carried thereby, the worm shaft being supported upon the sub-link, a longitudinally extending shaft on the sub-link having a worm at one end engaged by the last named worm wheel and at its other end having a bevel pinion, a shaft extending transversely of and carried by the sub-link and having a bevel gear wheel at one end engaging said bevel pinion and carrying a bevel gear wheel at its other end, an auxiliary electric motor having an armature shaft carrying a bevel pinion engaging the last named bevel gear wheel, a reversing controller for the motor, bevel gear wheels mounted loosely upon the transverse shaft, a manually operable clutch whereby either one of the last bevel gear wheels may be engaged operatively with the shaft, and a power operated shaft extending longitudinally of the machine and having a bevel pinion meshing with both of the last named bevel gear wheels.
3. In testimony whereof I hereunto affix my signature.

JAMES E. DILLON.
